DESIGN FOR AN ATOMIZER

Robert P. Vuillemenot, New York, N. Y., assignor to The De Vilbiss Company, Toledo, Ohio, a corporation of Ohio

Application November 17, 1937, Serial No. 72,960

Term of patent 3½ years

To all whom it may concern:

Be it known that I, Robert P. Vuillemenot, a citizen of the United States and resident of New York, in the county of New York and State of New York, have invented a new, original, and ornamental Design for an Atomizer, of which the following is a specification, reference being had to the accompanying drawing, forming a part thereof.

In the drawing, Figure 1 is a side elevational view of an atomizer showing my new design; and Figure 2 is a front elevation thereof.

The essential feature of my new design resides in the portions shown in full lines.

I claim:

The ornamental design for an atomizer, substantially as shown and described.

ROBERT P. VUILLEMENOT.
